UNITED STATES PATENT OFFICE.

HARRISON J. MITCHELL, OF BELOIT, WISCONSIN, ASSIGNOR TO P. B. YATES MACHINE COMPANY, OF BELOIT, WISCONSIN, A CORPORATION OF WISCONSIN.

SIDE-HEAD HOLD-OVER AND CHIP-BREAKER-LIFT STRUCTURE.

1,205,651.

Specification of Letters Patent. Patented Nov. 21, 1916.

Application filed October 6, 1915. Serial No. 54,318.

To all whom it may concern:

Be it known that I, HARRISON J. MITCHELL, a citizen of the United States, residing at Beloit, in the county of Rock and State of Wisconsin, have invented certain new and useful Improvements in Side-Head Hold-Over and Chip-Breaker-Lift Structures, of which the following is a specification.

In woodworking machines employing side-heads for planing the edges of boards, it has been customary to use chipbreakers or board-holding devices, but experience has shown that, particularly with a rapid feed of lumber, such chipbreaker is likely to be struck a sharp blow by the entering board, especially when the front end of the board recedes or backs away from the side-guide as it is being advanced.

One of the prime aims of this invention is to provide means to hold the board over properly against the guide or gage and to relieve the chipbreaker from the shock incident to the engagement of the board therewith, such means being constructed to receive and reduce the jar produced by the board striking it. With this and other objects in view, I have devised structures for accomplishing these purposes, and in the accompanying drawing forming a part of this specification, I have illustrated a desirable embodiment of the invention.

In this drawing, Figure 1 is a fragmentary plan view of the improved appliance with the chipbreaker hood shown in section, and Fig. 2 is a vertical section on line 2—2 of Fig. 1, the parts being viewed in the direction indicated by the arrows.

In this construction, the two planing side-heads are supplied with the reference characters 10 and 11, the machine being equipped with the usual cut-bars 12, 12, and the side-guide 13, on which is adjustably mounted the nose-piece or bar-before-cut 14.

On the side of the machine opposite the guide or gage 13, a chipbreaker hood 15 is hinged at 16 on any suitable part of the machine, such hood having the usual aperture 17 for the discharge of the shavings. At its end the hood or cover has two outstanding spaced ribs 18 and 19 between which the reduced shank 20 of a chipbreaker 21 is accommodated, such shank being hinged or pivoted to the ears 18 and 19 by means of a hinge-pin 22. The upper-rib 18 is slotted at 23, the slot receiving a screw

24 secured to the chipbreaker shank, and by means of which the angular position of the chipbreaker with reference to the hood may be adjusted.

At 25 a link 26 is pivoted to the chipbreaker and is disposed beneath it as illustrated, the free end of the link carrying a roller 27 freely revoluble on a stud 28 and adapted to engage the edge of the incoming lumber and hold it over against the guide, as well as constituting a lift device or shifter for the chipbreaker.

The shank 20 of the chipbreaker has an apertured ear 29 through the hole of which extends an eye-bolt 30, the eye end of which fits over a pin 31 carried by the link and extended downwardly through perforated bosses 32 and 33. The protruding end of the bolt is equipped with a nut 34 and its associated lock-nut 35, the former constituting a stop or limiting device adapted under certain conditions to engage the adjacent face of ear 29. This ear has a depending lug 36 intended to coöperate with the edge of link 36 and constitute a companion stop for the appliance.

To the lower end of pin 31 a chain 37 is fastened in any approved manner, such chain passing over a sheave and bearing a weight tending to pull the parts over toward the work, that is, toward the elements 10, 14, and 13, illustration of the sheave and weight being omitted. It will be noticed that the pull of this chain acts both on the roller 27 and the chipbreaker, pressing both of them toward their work. It should also be observed that the roller 27 has a predetermined amount of play with reference to the chipbreaker, the extent of such lost motion being determined by the position of the stops 36 and 34.

In Fig. 1, I have shown the side-heads acting on a board 38, a somewhat wider board 39 being advanced for the planing of its edges. The parts of the appliance are so constructed and positioned, that, if the following board is only slightly narrower or slightly wider than the preceding board, the edge of which the chipbreaker is engaging, the roller 27 will act to push its board over properly against the guide 13 without disturbing the position of the chipbreaker, this action being possible by reason of the limited freedom of movement of the roller with respect to the chipbreaker. Of course, when

the board under the roller reaches the chip-breaker, if such board is wider than the preceding one, it will lift or shift the breaker by direct engagement therewith, permitting 5 it to ride properly on its edge, and if such second board is narrower than the leading board, the chipbreaker will move over under the action of chain 37 into correct engagement with its edge, as soon as the breaker is 10 free from the wider planed board.

In case the following board is considerably wider than the first board, in advancing, it will contact with the roller 27, which will force it over against the guide 13, but such 15 engagement of the board with the roller will move or shift the chipbreaker away from the edge of the first board. Inasmuch, however, as the planing of that board is close to the end of the latter, no harm results, it being more important that the second board is pressed against the guide as it passes to the chipbreaker and side-heads. If, on the other hand, the second board is 20 considerably narrower than the preceding one, it will be first engaged by the roller to properly coöperate with the guide 13, as soon as this action is permitted by the chip-breaker riding off of the end of the preceding board, and immediately thereafter the 25 chipbreaker will contact with the board. It should be clear, therefore, that the roller 27 constitutes both a hold-over device and a chipbreaker lift or shifter.

It should be remembered that the device 30 illustrated and described is merely illustrative of one way in which the invention may be put into practicable form, but it is also capable of various other embodiments working upon the same general principles and containing in general the benefits 35 and advantages referred to.

I claim:

1. In an appliance of the character described, the combination of a guide against 40 which an edge of the work is adapted to bear, a movably-mounted chipbreaker adapted to coöperate with the opposite edge of the work, means constructed to bear against said latter edge of the work in advance of the chipbreaker and press the work over to the guide, said means and chipbreaker being adapted to co-act with the work at the same time, and means common to said chipbreaker and pressing-means acting to force both the chipbreaker and pressing-means toward the edge of the work, substantially as described.

2. In an appliance of the character described, the combination of a guide against 50 which an edge of the work is adapted to bear, a movably-mounted chipbreaker adapted to coöperate with the opposite edge of the work, means constructed to bear against said latter edge of the work in advance of the chipbreaker and press the work

over to the guide, said means and chip-breaker being adapted to co-act with the work at the same time, means common to said chipbreaker and pressing-means acting to force both the chipbreaker and pressing-means toward the edge of the work, and means enabling said pressing-means to actuate said chipbreaker away from the work, substantially as described.

3. In an appliance of the character described, the combination of a guide against which an edge of the work is adapted to bear, a chipbreaker mounted to be capable of movement toward and from and adapted to coöperate with the opposite edge of the work, means constructed to bear against said latter edge of the work in advance of the chipbreaker and press the work over to the guide, said means and chipbreaker being adapted to co-act with the edge of the work 75 at the same time, means supporting said pressing-means on said chipbreaker mounting and movable relatively thereto, and means common to said chipbreaker and pressing-means acting to force both the chipbreaker and pressing-means toward the edge of the work, substantially as described.

4. In an appliance of the character described, the combination of a movable chip-breaker, means adapted to bear against the work in advance of the chipbreaker and press the work over to the guide, an equalizer common to said chipbreaker and pressing means, and means acting on said equalizer tending to force both the chipbreaker 85 and the pressing means toward the work, substantially as described.

5. In an appliance of the character described, the combination of a movable chip-breaker, means adapted to bear against the work in advance of the chipbreaker and press the work over to the guide, an equalizer common to said chipbreaker and pressing means, means acting on said equalizer tending to force both the chipbreaker and pressing means toward the work, and a loose connection between said equalizer and chip-breaker, substantially as described.

6. In an appliance of the character described, the combination of a pivoted chip-breaker, an equalizer pivoted to the chip-breaker, a roller mounted on said equalizer adapted to bear against the work in advance of the chipbreaker and press the work toward the guide, and means acting on said equalizer tending to force both the chip-breaker and the roller toward the work, substantially as described.

7. In an appliance of the character described, the combination of a pivoted chip-breaker, an equalizer pivoted to the chip-breaker, a roller mounted on said equalizer adapted to bear on the work in advance of the chipbreaker and press the work over to the guide, means acting on said equalizer 125

tending to force both the chipbreaker and roller toward the work, and a loose connection between said equalizer and chipbreaker, substantially as described.

5 8. In an appliance of the character described, the combination of a pivoted chipbreaker movable toward and from the work and having a projecting lug, an equalizer pivoted to said chipbreaker, a roller on said

equalizer adapted to bear against the work 10 in advance of the chipbreaker and press the work over to the guide, means acting on said equalizer tending to force both the chipbreaker and pressing means toward the work, and a loose connection between said 15 equalizer and lug, substantially as described.

HARRISON J. MITCHELL.
